TURBINE COOLING SYSTEM

Nicholas R. Dolida, Flushing, N.Y., assignor to Curtiss-Wright Corporation, a corporation of Delaware

Application January 26, 1954, Serial No. 406,283

8 Claims. (Cl. 253—39.15)

This invention relates to turbine apparatus and is particularly directed to a gas turbine construction having means for liquid cooling the turbine.

The power output and thermal efficiency of a gas turbine engine can be increased by increasing the temperature of its turbine motive fluid. In general, however, any such increase is limited by the maximum permissible operating temperature of the turbine blades and the turbine rotor disc. An object of the present invention comprises the provision of a novel turbine apparatus having means for liquid cooling the turbine rotor blades and/or turbine disc without requiring the transfer of the cooling liquid across relatively moving parts. A still further object of the invention comprises the provision of a novel liquid cooled turbine construction in which liquid sealed within the turbine rotor is circulated through the turbine rotor disc and/or the turbine rotor blades in response to the centrifugal forces acting on said liquid and in which a cooling medium is passed through a stationary member in heat exchange relation with said sealed rotor liquid.

Other objects of the invention will become apparent upon reading the annexed detailed description in connection with the drawing in which:

Fig. 1 is a partial axial sectional view through a two-stage turbine embodying the invention;

Fig. 2 is a sectional view taken along line 2—2 of Fig. 1;

Fig. 3 is a schematic development taken along line 3—3 of Fig. 1;

Fig. 4 is an enlarged sectional view of the peripheral bladed portion of one of the turbine rotor stages, showing one blade partially in section;

Fig. 5 is a developed view taken along line 5—5 of Fig. 4;

Fig. 6 is an enlarged view of a portion of Fig. 1;

Fig. 7 is a view taken along line 7—7 of Fig. 6;

Fig. 8 is a view similar to a portion of Fig. 6 but illustrating a modified construction;

Fig. 9 is a view illustrating the addition of check valves to certain of the rotor passages; and

Fig. 10 is a view similar to Fig. 4 but of a modified blade construction.

Referring to the drawing, reference numeral 10 designates the two-stage rotor of a gas turbine engine having a first stage rotor disc 12 and a second-stage rotor disc 14 with each of said stages being drivably connected to a stub shaft 16, said shaft extending into and through the rotor discs to form a hub for said discs. The turbine stub shaft 16 is splined to the turbine shaft 18 and the turbine rotor is supported by a bearing 20 disposed about the turbine shaft 18, said bearing being mounted in a fixed support member schematically indicated at 22.

A plurality of circumferentially-spaced blades 24 are secured to and extend radially outwardly from the periphery of the turbine rotor disc 12 as illustrated in Figs. 4 and 5. A similar plurality of blades (not illustrated) ex-

2

tend radially outwardly from the periphery of the turbine rotor disc 14. The turbine motive fluid flows axially between the turbine rotor blades and coacts with said blades to drive the turbine rotor. In a conventional gas turbine engine, the turbine rotor drives an air compressor which in turn supplies compressed air to the turbine combustion chamber and the hot gases discharging from said chamber constitute the turbine motive fluid. The gas turbine engine and rotor structure so far described is conventional.

The first-stage turbine rotor disc 12 has a plurality of circumferentially-spaced pairs of radially extending passages 26 and 28, said passages extending radially outwardly through the rotor hub 16 and disc 12 to the periphery of said disc. Four such pairs of passages spaced 90° apart are illustrated. The second-stage turbine rotor disc 14 has a similar plurality of circumferentially-spaced pairs of passages 30 and 32 staggered 45 degrees from the passages of the first-stage rotor disc 12, as shown in Figs. 2 and 3.

Each rotor passage 26 terminates at its radially outer end at the periphery of the first stage rotor disc 12 in an annulus 34 formed by a ring 36 secured on one side of said rotor adjacent to its periphery. Likewise each rotor passage 28 terminates at its radially outer end in an annulus 38 formed by a ring 40 secured to the other side of the rotor disc 12 at the periphery of said disc. Also each blade 24 secured to the periphery of the rotor disc 12 has passages 42, 44 and 46 extending longitudinally therethrough toward the radially outer end of the blade, each passage 42 being disposed adjacent to the center of its blade and each passage 44 and 46 being disposed adjacent to an edge of its blade. Each blade passage 42 communicates with the rotor annulus 34 through a passage 48 in the rotor disc 12, there being one such passage 48 for each blade 24. Similarly each blade passage 44 and 46 communicates with the rotor annulus 38 through passages 50 and 52 in the rotor disc 12, there being one set of rotor disc passages 50 and 52 for each blade 24. Also each blade 24 has a passage 47 adjacent to its radially outer end interconnecting the blade passages 42, 44 and 46.

Preferably, each blade of the second stage rotor disc 14 has passages similar to the passages 42, 44, 46 and 47 of the first stage blades 24 and in addition said second stage rotor disc has passages similar to the passages 34, 38, 48, 50 and 52 connecting its blade passages with its radial passages 30 and 32.

The bore through the rotor hub 16 is divided into concentric annular spaces by co-axial outer and inner cylindrical tubular members 60 and 62. The tubular member 60 has ribs 64 extending axially along its outer surface and engaging the inner surface of the bore through the rotor hub 16, said ribs forming passages 66 therebetween. The tubular member 62 extends axially beyond the ends of the member 60 and rings 68 and 70 are secured between the member 62 and the rotor hub 16 to enclose the space therebetween. The rings 68 and 70 are axially spaced from the ends of the member 60 so that the annular space between the member 60 and the bore of the rotor hub 16 is in communication with the annular space between the members 60 and 62 around the ends of the member 60. The annular space between the members 60 and 62 is partitioned by fins 72 extending axially along the outer surface of the member 62 and radially toward the member 60. The end rings 68 and 70 and tubular members 60 and 62 are secured together, as by brazing, to form a unitary structure which can readily be inserted within the rotor hub 16.

The end ring 70 has a plurality of radially extending ears 74 which are secured to the hub 16 as by screws 75 (shown in Fig. 7) whereby the unitary structure of

tubular members 60 and 62 and the end rings 68 and 70 are rotatable as a unit with the turbine rotor. The end ring 68 has a plurality of openings 76 therethrough and an annular bellows construction 78 is connected to the ring 68 across said openings. In addition, a spring 80 is disposed in compression between a plate 82 connected across the end of the bellows 78 and a plate 84, said latter plate bearing against a shoulder 86 within the rotor hub 16.

As illustrated the number of ribs 64 is equal to the number of pairs of rotor disc passages 26 and 28 plus the number of pairs of rotor disc passages 30 and 32 and the ribs 64 are so spaced circumferentially that each inter-rib passage 66 is in alignment with one of said pairs of rotor disc passages. Also, those inter-rib passages 66 aligned with a pair of rotor disc passages 26 and 28 have partitions 94 thereacross between its associated pair of said rotor disc passages. The alternate inter-rib passages 66 are each aligned with a pair of rotor disc passages 30 and 32 and each said alternate passage has a partition 96 between its associated rotor disc passages.

The passages within the rotor hub 16 formed by the annular members 60 and 62 together with the rotor disc passages 26, 28, 30, 32, 34, 38, 48, 50 and 52 and the rotor blade passages 42, 44, 46 and 47 are filled with a suitable liquid as for example water. For filling said passages, a combination valve and filler member 100 and a combination valve and vent member 102 are provided. In order to fill said passages, the members 100 and 102 are unscrewed a limited extent from their closed positions illustrated in Fig. 1 and then the liquid under pressure is supplied through the member 100 to fill said rotor passages with liquid while the gas in said passages escapes through the vent member 102. After said rotor passages are filled with liquid the members 100 and 102 are screwed down against their valve seats to their positions illustrated thereby sealing said liquid within the rotor. The spring 80 functions to keep the liquid within the rotor under pressure and the annular space 104 within the bellows 78 functions as an expansion chamber for said liquid.

A stationary hollow member 110 extends into the rotor hub in contact with the rotor tubular member 62, said member comprising a hollow shaft-like member 110 having a plurality of circumferentially-spaced fins 112 extending axially along the member 110 and radially outwardly therefrom and also comprising a sleeve member 114 fitted over and extending axially beyond the fins 112. A plug 116 is fitted within the sleeve member 114 adjacent to the inner end of said member but spaced from the adjacent end of the shaft-like member 110 so that the bore through the member 110 is in communication with the finned space about said member around the inner end of said member.

A pump 120 is connected, by means schematically indicated at 122, to the outer end of the shaft-like member 110 for supplying a relatively cool liquid thereto. The outer end of the sleeve member 114 has an outlet conduit connection 124 for outflow of said cooling fluid whereby said cooling fluid flows into the shaft-like member 110 and then around the inner end of said member and axially along the finned space about said member and thence through the outlet conduit 124.

The outer surface of the sleeve member 114 is disposed adjacent to the inner surface of the rotor tubular member 62 for good heat transfer therebetween. With this construction, if the liquid circulated through the stationary member 110 is sufficiently cool, said liquid will remove heat from the liquid in the rotor hub. The heat transfer path from the liquid in the rotor hub to said cooling liquid is through the rotor hub fins 72 and the wall of the rotor hub member 62 to the wall of the stationary sleeve member 114 and its associated fins 112 to the cooling liquid. Thus the stator structure 110, 112, 114 and 116 and the adjacent rotor structure constitutes a heat exchange structure utilizing a liquid cool-

ing medium for extracting heat from the rotor liquid. Preferably the portions of said stator structure passage outside the turbine rotor are shielded by heat insulating material as indicated at 126. Any suitable cooling medium may be used. For example, liquid fuel supplied to the combustion chamber of the gas turbine engine may be circulated through said stator heat exchange structure on its way to said combustion chamber.

The fins 72 and 112 increase the efficiency of the heat transfer between the rotor liquid and the cooling medium. Said fins may be slotted to break up any boundary layer of liquid which might form therealong to decrease the heat transfer through said fins. In addition, for good heat transfer, the walls of the rotor and stationary members 62 and 114 respectively should be quite thin and the clearance between said walls should be as small as possible without the presence of excessive friction therebetween. Thus the clearance between said rotor and stator members preferably is of the order of magnitude of the clearances found in plain bearings. Also the heat transfer between the rotor liquid and the cooling medium is increased by increasing the length of contact of the rotor and stator members 62 and 114. Preferably the length of contact of said members 62 and 114 is at least several times the diameter of their contacting surfaces. Also lubricating oil or other material with lubricating properties preferably is disposed or passed between the rotor and stator members 62 and 114 at assembly to serve both as a lubricant between their relatively movable walls and as a medium for heat transfer between said walls.

During gas turbine operation, the leading and trailing edges of the turbine rotor blades 24 run hotter than the intermediate portions of the blades. Hence the liquid within the central passage 42 of each blade runs cooler and therefore more dense than the liquid in the other blade passages 44 and 46. Accordingly during rotor operation the centrifugal forces on the liquid within the rotor blades acts as a centrifugal pump to pump liquid radially outwardly through each blade passage 42 and then across its associated blade passage 47 and radially inwardly through its associated blade passages 44 and 46. The inner end of each blade passage 42 is connected to the rotor disc passages 26 through the annulus 34 and the inner ends of the blade passages 44 and 46 are connected to the rotor disc passages 28 through the annulus 38. In addition, the radially inner ends of each pair of rotor disc passages 26 and 28 are separated by a partition 94 but are in communication with each other around the ends of the rotor hub tubular member 60. Accordingly the passages of each rotor blade 24 form part of a loop passageway for said blade around which, during gas turbine operation, the turbine rotor liquid is pumped, the direction of the liquid circulation being indicated by the arrows in Figs. 1, 3 and 4. In a similar manner the rotor liquid circulates through the passages 30 and 32 of the rotor disc 14 and through its associated blade passages during gas turbine operation. As the rotor liquid flows axially along the rotor hub through the passages between the rotor fins 72 heat is transferred, as previously described, to the cooling fluid flowing in the opposite direction through the passages between the stationary member fins 112. In this way heat is continually removed from the relatively warm rotor liquid returning to the rotor hub as said warm rotor liquid flows along the inner surface of the rotor hub so that relatively cool rotor liquid is returned to the central rotor blade passages 42. Therefore, the differential between the liquid temperature in said rotor blade passage 42 and that in the associated passages 44 and 46 is maintained and the rotor liquid continues to circulate as described.

Gate-type valve means 128 may be provided in each of the passages 28 and 32 for regulating the rate of circulation of the rotor liquid coolant therethrough. Also the inner surface of the hollow shaft-like member 110

may be coated with a heat insulating material to minimize any heat transfer through the walls of said member. Likewise the outer surface of the rotor tubular member 60 may be similarly coated with heat insulating material.

With the rotor passages completely filled with liquid some boiling of the liquid may take place along the hot walls of the rotor blade passages. A limited amount of such boiling is desirable because additional heat is removed from said blade walls as heat transfer takes place as a result of local boiling along said walls.

As illustrated in Fig. 3 the ribs 64 separate the liquid circulating through the passages of the rotor disc 12 from that circulating through the passages of the rotor disc 14 in order that the relatively warm rotor liquid returning radially inwardly through the rotor passages 28 does not intermingle with the relatively cool liquid approaching the passages 30 of the rotor disc 14. With this construction the loop passageways through the rotor disc 12 are in parallel with the loop passageways through the rotor disc 14. However, since the blades of the second stage rotor disc 14 normally run considerably cooler than the blades of the first stage rotor disc 12 the second stage rotor disc is not in need of cooling to the same extent as the first stage rotor disc.

If a leak should occur in the liquid coolant passages of the turbine rotor during turbine operation, for example because of a turbine rotor blade failure, the turbine will quickly lose all or substantially all its liquid coolant. Under these conditions if operation of the turbine is continued at normal or full power excessive turbine blade temperatures will result. To prevent this means may be provided for energizing a signal circuit to warn the operator whenever the liquid coolant passages within the turbine rotor are not completely filled. For this purpose the end plate or plug 116 of the shaft-like stator member 110 may have a switch or contact 130 mounted thereon for engagement by the central portion 132 of the bellows end plate 82 for closing a warning or control circuit 134 when the passages of the turbine rotor are not completely full. With this arrangement, if a leak should occur in the liquid coolant passages of the turbine rotor, the spring 80 will force the bellows end plate 82 to the right (Figs. 1 and 6) to engage the switch or contact 130 to complete the warning signal or control circuit 134. Upon receiving a warning signal the operator can reduce the fuel flow to a safe value or the control circuit 134, when energized, can automatically limit the fuel flow to a low safe value.

In addition to the function of the spring 80 for closing the circuit 134 when a leak occurs in the passages of the rotor coolant system, the spring 80 normally maintains the liquid coolant in the turbine rotor under pressure. This raises the boiling temperature of said liquid coolant and increases the efficiency of the heat exchange system. In addition to or in lieu of the spring 80 the output pressure of the gas turbine power plant compressor may be used to pressurize the liquid coolant in the turbine rotor. Such an arrangement is shown in Fig. 8.

The structure of Fig. 8 is like that of Figs. 1-7 except the spring 80 has been replaced by a bellows 140. The left side (Fig. 8) of the bellows 140 is exposed to the output pressure of the turbine compressor (not illustrated) thereby forcing the bellows 140 against the bellows 78 to pressurize the liquid within the rotor passages.

In order to insure that circulation of the liquid coolant in the rotor starts in the right direction, that is in the direction indicated by the arrows in Fig. 1, suitable check valves may be added to the turbine rotor passages 26 and 30. Such a modification is illustrated in Fig. 9. The parts of Fig. 9 have been designated by the same reference numerals as the corresponding parts of Fig. 1 but with a subscript *a* added thereto.

Fig. 9 illustrates the first stage turbine rotor disc 12a with one of its liquid coolant passages 26a. At the radi-

ally inner end periphery of said disc the passage 26a is enlarged to receive a check valve housing structure 150 having a ball-type check valve 152 urged radially inwardly against a valve seat by a spring 154. The spring 154 is designed to hold its valve 152 in its closed position against centrifugal force until some low turbine speed is attained. As the check valve 152 opens, if flow of the liquid coolant starts in the wrong direction said valve will immediately close. Hence flow of the liquid coolant can only start in the direction indicated. Once started in the right direction the liquid coolant flow will continue in this direction even though the check valves are subsequently held in their open positions by the centrifugal force thereon when the turbine reaches its normal operating speed.

As best seen in Fig. 4 the outer ends of the passages 42, 44 and 46 of each blade are interconnected by their blade passage 47 to provide for circulation of the rotor liquid from one rotor blade passage to another blade passage. It is not essential, however, that the outer ends of the blade passages be interconnected. Fig. 10 illustrates a modification in which each rotor blade also has a dead-end passage. Except for this additional passage and its connection to the rotor disc passages the modification of Fig. 10 is like that of Figs. 1-7. Hence for ease of understanding the parts of Fig. 10 have been designated by the same reference numerals but with a subscript *b* added thereto as the corresponding parts of Figs. 1-7.

30 In the modification of Fig. 10 each blade 24b, in addition to the passages 42b, 44b, 46b and 47b, has a relatively short dead-end passage 160 adjacent to its trailing edge. The inner end of each blade dead-end passage 160 is connected to the rotor annulus 34b through a rotor disc passage 162. Circulation of liquid also takes place in such a dead-end passage because the liquid along its center runs cooler than that along its walls. Hence liquid circulates in each dead-end passage 160 in the manner indicated in Fig. 10. In addition, as indicated in Fig. 40 10, liquid also circulates through the other rotor blade passages 42b, 44b, 46b and 47b in a manner similar to the circulation through the corresponding passages of Figs. 1-7.

The addition of a dead-end passage 160 to each rotor blade has the disadvantage that the hot liquid returning along the walls of said passage to the annulus 34b raises the temperature of the liquid in said annulus thereby increasing the temperature of the liquid supplied to each blade passage 42b. However, because the trailing edge 50 of a rotor blade is quite thin, particularly at its outer end, it is difficult to place the relatively long liquid passage 46b sufficiently close to its blade trailing edge to adequately cool said edge. Hence the addition of the dead-end passage 160 to each rotor blade helps to cool the trailing edge of said blade.

While I have described my invention in detail in its present preferred embodiment, it will be obvious to those skilled in the art, after understanding my invention, that various changes and modifications may be made therein 60 without departing from the spirit or scope thereof. I aim in the appended claims to cover all such modifications.

I claim as my invention:

1. A turbine rotor having a plurality of circumferentially-spaced blades extending radially from the rotor and also having means forming a loop passageway rotatable with said rotor, said loop passageway forming means including a movable wall portion; liquid sealed within said passageway for cooling said rotor; and means 65 co-operable with said movable wall portion for urging said movable wall portion in a direction to pressurize said liquid.

2. Turbine apparatus comprising a turbine rotor having passage means for circulation of liquid therethrough for cooling said rotor, said passage means including a

wall portion movable to vary the volume of said passage means; means cooperable with said movable wall portion for applying a force thereto in a direction to reduce the volume of said passage means for pressurizing liquid therein; a stator structure having passage means disposed adjacent to at least a portion of said rotor passage means for heat exchange therebetween; and means for circulating a cooling liquid through said stator passage means for extracting heat from said rotor liquid.

3. Turbine apparatus comprising a turbine rotor having a hub portion, a plurality of circumferentially-spaced blades extending radially from the rotor periphery and passage means rotatable with said rotor, said rotor passage means including a rotor hub portion disposed adjacent to the rotor hub and other portions extending into said rotor blades and interconnected with said hub portion of the rotor passage means; liquid sealed within said passage means for cooling said blades; a stator structure having passage means with a wall portion disposed adjacent to and being axially coextensive with at least a part of said rotor hub portion of the rotor passage means for heat exchange therebetween; and means for circulating a cooling liquid through said stator passage means.

4. Turbine apparatus comprising a turbine rotor having an annular hub, a plurality of circumferentially-spaced blades extending radially from the rotor periphery and passage means rotatable with said rotor, said rotor passage means including a rotor hub portion disposed adjacent to and extending axially along the inner surface of said rotor hub and other portions extending into said rotor blades and interconnected with said hub portion of the rotor passage means; liquid sealed within said rotor passages means for cooling said blades; a stator structure extending into said rotor hub and having passage means with a wall portion disposed adjacent to and extending axially along said rotor hub portion of the rotor passage means for heat exchange therebetween; and means for circulating a cooling liquid through said stator passage means.

5. Turbine apparatus as recited in claim 4 and including a flexible diaphragm secured to the rotor hub and forming a wall closing one axial end of the hub portion of the rotor passage means and said apparatus also including means cooperable with said flexible diaphragm for applying a force thereto for pressurizing the liquid within said rotor passage means.

6. Turbine apparatus comprising a turbine rotor having an annular hub, a plurality of circumferentially-spaced blades extending radially from the periphery of said rotor and also having liquid passage means rotatable therewith; liquid sealed within said rotor passage means for cooling said blades; said rotor passage means includ-

ing a rotor hub portion disposed around and extending axially along the inner surface of said annular rotor hub, first and second radially extending passages within each rotor blade, passage means connecting the radial inner end of each blade first passage with one axial end of the rotor hub portion of said rotor passage means, and other passage means connecting the radially inner end of each blade second passage with the other axial end of the rotor hub portion of said rotor passage means, the outer ends of the first and second passages of each blade being connected to complete a loop passageway for said blade and the first and second passages of each blade being so disposed therein that during turbine operation said blade first passage is at a cooler portion of the blade so that the liquid within each blade first passage is at a lower temperature, and therefore at a higher density, than a liquid in the second passage of said blade whereby the centrifugal forces on the liquid causes the liquid to circulate through each blade in a direction radially outwardly through its first passage; a stator structure having a cylindrical portion extending into said annular rotor hub portion and having passage means disposed within and extending axially along said cylindrical portion adjacent to the rotor hub portion of said rotor passage means; and means for circulating a cooling medium through said stator structure passage means in heat exchange relation with the rotor liquid.

7. Apparatus as recited in claim 6 and including a flexible diaphragm secured to said rotor hub and forming a wall closing one axial end of the rotor hub portion of the rotor passage means and said apparatus also including means cooperable with said flexible diaphragm for applying a force thereto for pressurizing the liquid with said rotor passage means.

8. Apparatus as recited in claim 6 in which the axial length of the portion of said stator structure cylindrical portion within said rotor hub portion is at least twice its diameter.
